UNITED STATES PATENT OFFICE.

WILLIAM H. GARDINER, OF NEW YORK, N. Y.

DESIGN FOR A LAMP-CASING.

40,995.

Specification for Design.

Patented Nov. 22, 1910.

Application filed November 23, 1909. Serial No. 529,654. Term of patent 14 years.

To all whom it may concern:

Be it known that I, WILLIAM H. GARDINER, a citizen of the United States, residing at New York, in the county of New York and State of New York, have invented a new, original, and ornamental Design for Lamp-Casings, of which the following is a specification, reference being had to the accompanying drawing, forming part thereof.

Of the accompanying drawings, Figure 1 represents an elevation of a lamp casing showing my new design, and Fig. 2 represents a perspective view from a position at one side of Fig. 1.

The principal features of the design consist in the trumpet-shaped lower portion *a*,

and the bell-shaped cap or upper portion *b*, giving the casing as a whole the general appearance of a morning-glory or other trumpet-shaped flower, *a* corresponding to the corolla and *b* to the calyx.

I claim:

The ornamental design for a lamp casing as shown and described.

In testimony whereof I have hereunto set my hand in the presence of two subscribing witnesses this 22nd day of November, 1909.

WILLIAM H. GARDINER.

Witnesses:

EDWARD E. BLACK,
R. M. PIERSON.
